BALANCING EQUIPMENT FOR FOUR-WIRE CIRCUITS.

1,378,836.

Specification of Letters Patent. Patented May 24, 1921.

Application filed January 29, 1919. Serial No. 273,804.

To all whom it may concern:

Be it known that we, ALVA B. CLARK and CHARLES S. DEMAREST, both residing at Brooklyn, in the county of Kings and State of New York, have invented certain Improvements in Balancing Equipment for Four-Wire Circuits, of which the following is a specification.

This invention relates to repeater circuits and more particularly to arrangements whereby an operator may monitor, talk, and ring on transmission circuits which include as an element thereof a repeater circuit of the well known balanced type.

Where two stations are interconnected by means of a balanced repeater circuit such as a four-wire circuit, two transmission lines for transmitting in opposite directions and each including one-way amplifiers are connected at their ends to terminal two-wire lines. The terminal two-wire lines are balanced by means of artificial lines and if a sufficiently high degree of balance is provided it is possible to secure a gain in transmission between the terminal stations of the four-wire circuit without causing singing to take place over said circuit. Any considerable change in the condition of the terminal two-wire circuit may result in a degree of unbalance sufficient to cause singing to take place. The problem of associating monitoring, talking and ringing equipment with the two-wire line consequently involves difficulties which it is the purpose of this invention to overcome.

In general, the object of the invention is, therefore, to provide means whereby when the condition of the terminal two-wire portion of a balanced repeater circuit is changed, the circuit may still be maintained sufficiently balanced to prevent singing.

A particular object of the invention is to provide an arrangement whereby a listening apparatus of an operator's monitoring circuit may be associated with the terminal two-wire line of a balanced repeater system without causing appreciable unbalance.

A still further particular object of the invention is to provide means whereby an operator's talking equipment may be associated with the terminal two-wire line at one of the terminal stations of the four-wire circuit without causing singing to take place.

Still another particular object of the invention has reference to the provision of

means whereby a monitoring operator may apply ringing current to the terminal two-wire circuit of a balanced repeater system without causing appreciable unbalance.

An additional particular object of the invention is to provide means whereby, when the two-wire line is disconnected from the two-wire terminal of the balanced repeater circuit, the balanced condition of the circuit is still maintained.

These objects, as well as others more fully hereinafter appearing, are secured by means of the arrangements set forth in the following description which may be best understood by reference to the accompanying drawing, the figure of which is a diagrammatic illustration of a preferred embodiment of the invention.

Referring to the drawing, the apparatus at one terminal station of a four-wire circuit is shown, the four-wire circuit comprising a line L_e for transmitting in one direction to a distant station and a line L_w for transmitting in the opposite direction from the distant station. Each of these lines include one-way amplifiers (not shown) and are interconnected at their ends through a three winding transformer arrangement 10 to a terminal two-wire line such as L . The equipment at both terminal stations of the four-wire circuit will be substantially identical and will conform to that shown in the drawing. An operator's monitoring circuit M including a receiver R , transmitter T and controlling keys K_1 , K_2 , and K_3 terminates in a twin plug P adapted to coöperate with a twin jack J whereby the monitoring circuit may be bridged across the two-wire line L . The two-wire line L is normally balanced by an artificial line or network N and in order that the operator may listen in on the circuit without disturbing the balance, the normal connection of the monitoring circuit includes a high impedance transformer C which, when bridged across the line L , reduces the transmission over said line by such a small amount that no appreciable unbalance of the circuit results. In order that sufficient energy may affect the receiver R of the monitoring equipment, an amplifier A is provided which amplifies the currents to such a value as to produce a proper volume of sound in the receiver.

When the talking apparatus or the ringing apparatus of the monitoring equipment

is connected with the two-wire line by means of the proper controlling key, the condition of the two-wire line is quite materially changed due to the relatively low impedance of said talking and ringing apparatus. To prevent unbalance due to this condition, networks N_x and N' are provided, the former being interpolated in the two-wire portion of the circuit between the point of connection of the monitoring equipment and the four-wire circuit and the latter network being substituted for the usual artificial line N . The network N_x consists of series resistances and a shunt resistance so proportioned that the impedance of the portion of the circuit beyond the shunt resistance may vary considerably without the impedance of the whole combination differing materially from that of the resistance N' . For example, if the series resistance of the network N_x be made 1600 ohms and the shunt resistance be made 400 ohms and the resistance of the element N' be made 1800 ohms, no appreciable degree of unbalance will result whatever may be the condition of the circuit beyond the network N_x . If, for instance, the line L be entirely disconnected the effective impedance of the network N_x will be 2000 ohms. If, on the other hand, the shunt element of the network N_x be short circuited, the resultant impedance will still be 1600 ohms so that the maximum possible variation is 200 ohms above or below the impedance of the element N' . In order to provide for situations which necessitate the disconnection of the line L from the four-wire circuit for testing or other purposes, the jack J is so arranged that by inserting an idle single plug in the right hand half thereof, the networks N_x and N' will be associated with the four-wire circuit in order to maintain the balance thereof. Further details of the apparatus may be sufficiently understood from a description of the operation which is as follows:

Assuming that the operator desires to listen in on the circuit by means of the monitoring equipment M , the plug P is inserted in the jack J and the monitoring key K_1 is operated. A circuit is completed over the sleeve contacts of the plug and jack from ground through the winding of marginal relay 11, over said contacts, over sleeve conductor 12 and over the normal contact of key K_2 through high resistance 13 to battery. The resistance 13 is sufficiently high to prevent the actuation of the marginal relay 11 so that no circuit changes take place as a result of the closing of this circuit. The actuation of key K_1 completes a circuit over the lower make contact of said key for relay 14 which is energized and completes a filament circuit of amplifier A thereby rendering said amplifier operative.

The operator's receiver R is now associated with the line L over a circuit including conductors 15, make contacts of key K_1 , conductors 16, autotransformer 17, amplifier A , high impedance transformer Q , conductors 18, back contacts of relay 19, tip contacts of plug O and jack J , and conductors 20. The primary winding of transformer C is bridged directly across the line L but the transformer is of such high impedance that but little transmission loss results and consequently no appreciable unbalance between the line L and the artificial line N occurs. The voltage induced in the winding of the transformer which is connected to the grid of the amplifier A causes a current to flow through the receiver R such as to produce the desired volume of sound in said receiver. Should the operator desire to talk over the two-wire line L or over the four-wire circuit, key K_1 will be restored and the key K_2 will be actuated. By restoring key K_1 the receiver R is bridged about one half of one of the windings of the induction coil 21 of the operator's set, the transmitter T of said operator's set being associated through said transformer with conductors 22. The actuation of key K_2 closes at its lower contact a circuit from battery through low resistance 23, lower make contact to key K_2 , conductor 12, sleeve contacts of plug P and jack J , through the winding of marginal relay 11 to ground. Resistance 23 is sufficiently low to permit of the energization of marginal relay 11 which completes a circuit from ground over its front contact and through the windings of relays 24 and 25 to battery. Relay 11 also completes a circuit for the relay 26. The relays 24 and 25 at their front contacts open the direct connection between the two-wire terminals 27 of the four-wire circuit and the line L and interpolate the network N_x . Relay 26 disconnects the artificial line N and substitutes the balancing element N' in its stead.

The actuation of key K_2 also closes the circuit from ground over the upper make contact of said key, over conductor 29 and through the winding of slow acting relay 19 to battery. As soon as relay 19 operates a circuit will be completed in parallel with the shunt resistance element of network N_x as follows:

Over the front contacts of relay 24, back contacts of relay 28, conductors 20, tip contacts of jack J and plug P , front contacts of relay 19, normal contacts of key K_3 , conductors 30, make contacts of key K_2 and over conductors 22 to the operator's set including transmitter T and receiver R .

The parallel circuit above traced is of comparatively low impedance but as has been already explained the series and shunt elements of the network N_x are so proportioned

with respect to each other and the element N' that the degree of unbalance is negligible regardless of the character of the circuit connected in parallel with the shunt element of the network N_x . Consequently, the low impedance operator's set may be connected across the two-wire line enabling the operator to talk either over the two-wire line or the four-wire circuit without causing singing to 10 take place.

It will be noted with reference to the operations just described, that the relay 19 is slow acting so that it permits relays 24, 25 and 26 to operate and connect networks N_x and N' in circuit before the low impedance operator's set is bridged across the two-wire line. This prevents the possibility of a singing condition being set up due to the fact that the operator's set is bridged across the 20 two-wire line before the relays 24, 25 and 26 have had time to operate and connect the networks N_x and N' in circuit.

Should the operator desire to transmit a ringing signal either over the four-wire circuit to the distant terminal station thereof or over the two-wire line L to the station in which said line terminates, the ringing key K_3 will be operated. A circuit is completed over the upper make contact of said key from 30 battery through the low resistance 23, over conductor 31, make contact of key K_3 to point 32, thereby completing a low resistance path to the sleeve conductor 12 in parallel with the high resistance path through resistance 13. The current flow over sleeve conductor 12 and through the winding of relay 11 is thereby increased so that marginal relay 11 is actuated and completes circuits for relays 24, 25 and 26 as previously described. Relays 24, 25 and 26 operate to connect networks N_x and N' into the circuit in a manner already set forth. Key K_3 at its lower make contact also completes a circuit for the slow acting relay 19 which, after an 40 interval, completes a circuit for ringing current over the inner make contacts of key K_3 , front contacts of relay 19, tip contacts of plug P, jack J and over conductors 20 to points 33 and 34 at which points the current 50 divides, part flowing over the line L to the distant station and part flowing over the back contacts of relay 28, front contacts of relay 24, through network N_x , front contacts of relay 25, over conductors 27 through the 55 bridge 35 and through the winding of ringing responsive relay 36. The current flowing over the line L may actuate ringing responsive means at the distant station to call the attention of the operator at said station. The 60 current flowing through the relay 36 actuates said relay to open the normally closed circuit of relay 37 which, upon releasing its armature completes a circuit for relays 38 and 39. Relay 39 disconnects the autotransformer 40 and ringing responsive relay 41.

from bridge 35 to prevent the actuation of ringing responsive relay 41. Relay 38 at its lower front contacts completes a circuit for the generating apparatus 42 and at its upper front contact completes a circuit for the 70 relay 43 whereby ringing current from the generating apparatus 42 is transmitted through the transformer 44 and over the front contacts of relay 43 to the line L_e . The ringing current transmitted over the line L_e 75 upon arriving at the distant station operates ringing responsive apparatus at said station in a manner which will be presently made clear in connection with the description of the operations resulting from the transmission of ringing current from said distant station to actuate similar ringing responsive apparatus at the station illustrated in the drawing.

The connection of the relatively low impedance ringing path over the make contact key K_3 to the line L does not cause the four-wire circuit to sing for the reason that said low impedance path is connected in parallel with the shunt element of network 90 N_x so that a fair degree of balance is maintained in a manner similar to that described in connection with the operator's talking apparatus.

Should ringing current be transmitted 95 from the distant station of the four-wire circuit over the line L_w said ringing current would flow through the autotransformer 40 and through the windings of ringing responsive relay 41 to actuate said relay. Relay 100 41 would thereupon open the circuit of relay 45 which, in turn, completes the circuit of relays 46 and 39. Relay 39 disconnects the autotransformer and relay 41 from the bridge 35 thereby preventing the current 105 flowing from the line L_w from being transmitted to the line L_e . Relay 46 at its upper front contact completes circuits for relays 24, 25 and 26 thereby interpolating the network N_x in the line L and substituting the balancing element N' for the artificial line N . Relay 46 at its lower front contact completes a circuit from ground over the upper front contact of relay 25 and through the winding 110 of relay 28. Relay 28 disconnects the two-wire line L from the four-wire circuit and connects ringing current to the two-wire line over the outer front contacts of relay 24 and over the inner front contacts of relay 28 so that ringing current is transmitted to the station at which the line L terminates. The unbalance of the four-wire circuit which would ordinarily be produced by the disconnection of the two-wire line L from the four-wire circuit at the contacts of relay 28 is prevented 115 by reason of the fact that networks N_x and N' have been previously connected in circuit.

Singing over the four-wire circuit is, therefore, prevented during the ringing operation. It is sometimes necessary to disconnect the 130

two-wire line from the four-wire circuit for purposes of testing or making repairs. Should the two-wire line L be disconnected from the four-wire circuit at switching 5 points 47 and 48 for instance, singing of the four-wire circuit may be prevented by previously inserting an idle plug in the right hand half of the twin jack J. This operation would complete a circuit from battery 10 through resistance 49, make contact 50, normal contact 51 and through the winding of marginal relay 11 to ground. Marginal relay 11 would be energized by the circuit thus completed and would operate relays 24, 25 15 and 26 to connect networks N_x and N' in circuit to balance the four-wire system.

By means of the arrangements above described, a simple and efficient means is provided for maintaining a reasonable degree of 20 balance of a four-wire circuit regardless of changes in the condition of the equipment connected to the two-wire terminals of the circuit and while the invention has been illustrated in what is thought to be its most 25 desirable form, it will be obvious that the general principles thereof may be embodied in many organizations widely different from that disclosed without departing from the spirit of the invention as defined in the following claims:

What is claimed is:

1. In a signaling system, a repeater circuit, terminal two-wire lines connected to the repeater circuit, means for balancing said two-wire lines, an operator's listening set, means for connecting said listening set with one of said two-wire lines, and a high impedance transformer in said connection to prevent appreciable unbalance of the repeater circuit.
2. In a signaling system, a repeater circuit, terminal two-wire lines connected to the repeater circuit, means for balancing said two-wire lines, an operator's listening set, means for connecting said listening set with one of said two-wire lines, a high impedance element in said connection to prevent appreciable unbalance of the repeater circuit, and an amplifier for amplifying currents received through said high impedance.
3. In a signaling system, a repeater circuit, terminal two-wire lines connected to the repeater circuit, means for balancing said two-wire lines, an operator's talking set of low impedance, means for connecting said set 55 with one of said two-wire lines, and means responsive to such connection to associate auxiliary balancing equipment with the circuit to prevent appreciable unbalance of the repeater circuit.
4. In a signaling system, a repeater circuit, terminal two-wire lines connected to the repeater circuit, means for balancing said two-wire lines, an operator's talking set of low impedance, means for connecting said set 60 with one of said two-wire lines, and means

responsive to such connection to include an auxiliary net work in the two-wire line between the talking set and the repeater circuit to prevent appreciable unbalance of the repeater circuit.

5. In a signaling system, a repeater circuit, terminal two-wire lines connected to the repeater circuit, means for balancing said two-wire lines, an operator's talking set of low impedance, means for connecting 70 said set with one of said two-wire lines, and means responsive to such connection to include an auxiliary network in the two-wire line between the talking set and the repeater circuit and to substitute an auxiliary 75 balancing means for said first balancing means in order to prevent appreciable unbalance of the repeater circuit.

6. In a signaling system, a repeater circuit, terminal two-wire lines connected to 80 the repeater circuit, artificial lines for balancing said two-wire lines, an operator's equipment of low impedance, a key for controlling the connection of said equipment with one of said two-wire lines, means responsive to the action of said key for including an auxiliary network in the two-wire line between the point of connection of the operator's equipment and the repeater circuit to prevent appreciable unbalance of 90 the repeater circuit, and to thereafter connect the operator's equipment with the two-wire line.

7. In a signaling system, a repeater circuit, terminal two-wire lines connected to 100 the repeater circuit, means for balancing said two-wire lines, an operator's ringing equipment, means for connecting said equipment with one of said two-wire lines, and means responsive to such connection to associate auxiliary balancing equipment with the circuit to prevent appreciable unbalance of the repeater circuit.

8. In a signaling system, a repeater circuit, terminal two-wire lines connected to 110 the repeater circuit, means for balancing said two-wire lines, an operator's ringing equipment, means for connecting said equipment with one of said two-wire lines, and means responsive to such connection to include an auxiliary network in the two-wire line between the point of connection and the repeater circuit to prevent appreciable unbalance of the repeater circuit.

9. In a signaling system, a repeater circuit, terminal two-wire lines connected to 120 the repeater circuit, means for balancing said two-wire lines, means to disconnect one of said two-wire lines from the repeater circuit, and means whereby an auxiliary balancing means may be connected to the two-wire terminal of the repeater circuit when the two-wire line is disconnected.

10. A transmission circuit including lines 130 interconnected by repeater apparatus, means

to balance said lines, an operator's listening set, means for connecting said listening set with one of said lines, and a high impedance transformer in said connection to prevent appreciable unbalance of said line.

11. A transmission circuit including lines interconnected by repeater apparatus, means to balance said lines, an operator's listening set, means for connecting said listening set with one of said lines, a high impedance ele-

ment in said connection to prevent appreciable unbalance of said line, and an amplifier for amplifying currents received through said high impedance.

In testimony whereof we have signed our names to this specification this twenty-eighth day of January, 1919.
